US0D1081589S

(12) **United States Design Patent** (10) **Patent No.:** **US D1,081,589 S**
(45) **Date of Patent:** ** *Jul. 1, 2025

(54) **ETHERNET SPLITTER**

(71) Applicant: **Shaoqiang Lin**, Fujian (CN)

(72) Inventor: **Shaoqiang Lin**, Fujian (CN)

(*) Notice: This patent is subject to a terminal disclaimer.

(**) Term: **15 Years**

(21) Appl. No.: **29/908,939**

(22) Filed: **Jan. 16, 2024**

(51) **LOC (15) Cl.** 13-03

(52) **U.S. Cl.**

USPC **D13/147**

(58) **Field of Classification Search**

(57)

CLAIM

The ornamental design for a ethernet splitter as shown and described.

DESCRIPTION

FIG. 1 is a perspective view of a ethernet splitter 1 to 2 showing my new design;

FIG. 2 is another perspective view thereof;

FIG. 3 is a front and back view thereof;

FIG. 4 is a left and right view thereof;

FIG. 5 is a top plan view thereof; and,

FIG. 6 is bottom plan view thereof.

(Continued)

The broken lines depict portions of the ethernet splitter 1 to 2 and form no part of the claimed design.

1 Claim, 6 Drawing Sheets
